UNITED STATES PATENT OFFICE.

WILLIAM COOPER, OF DENVER, COLORADO.

ROAD-MAKING MACHINERY.

1,117,333.

Specification of Letters Patent. Patented Nov. 17, 1914.
Application filed May 14, 1914. Serial No. 838,420.

To all whom it may concern:

Be it known that I, WILLIAM COOPER, citizen of the United States, and residing in the city of Denver, in the county of Denver and State of Colorado, have invented or discovered new and useful Improvements in Road-Making Machinery, of which the following is a specification.

My invention consists in a new and improved road making machine.

One method of making roads is to first plow up the road surface; then saturate the same with oil or other hydrocarbons in a fluid state, and then roll the material to a smooth, hard surface. This method has proved efficient in the case of both macadamized and dirt roads, but the expense has been very considerable owing to the number of workmen, the time and the apparatus required.

My invention consists in a machine which in one operation loosens and tears up the road surface, saturates the same deeply with oil and rolls the same hard and smooth again.

In the accompanying drawings, Figure 1 is a side elevation of the machine, certain parts being broken away in section for the sake of clearness; Fig. 2 is a plan view, partly in section of the rear scarifying roller and its mounting, the tender box being removed; Fig. 3 is a vertical section of the same along the line III—III in Fig. 2; Fig. 4 is an enlarged detail section of a portion of one of the scarifying teeth showing the method of mounting the same; Fig. 5 is a sectional detail of one of the scarifying rollers, and Fig. 6 is a longitudinal section of one of the pressure control cylinders.

The following is a detailed description of the drawings.

The machine is composed of two main elements; the scarifier and saturator A and the surface of B which trails after and is preferably drawn by the former. The element A is preferably of the following general structure: 1 is the main frame upon which is mounted the source of locomotion and power, such as the steam engine outfit 2. The front of frame 1 is provided with a pivoted yoke 1* in which is journaled the front scarifier C. The rear scarifier is journaled between the sides of the frame 1 toward the rear thereof. The structure and mounting of the two scarifiers is substan-

tially identical and therefore I will describe the same in detail in connection with the rear scarifier D. The scarifier is mounted on an axle or spindle 3 whose ends are enlarged and cylindrical to form hubs 4 which receive the cylindrical bearing blocks 5 mounted at either end of the axle 3 on the frame 1. Mounted on the axle 3 is a collar 6 which is provided with sockets 7 in which are secured the inner ends of spokes 8 which extend and are attached to the perimetral wall 9 of the scarifier. I have shown said spokes broken away for the sake of clearness. The inner face of the perimetral wall 9 is provided with a plurality of longitudinal integral oil chambers 10 whose ends are closed but which are connected with the bores of hubs 4 by means of feed tubes 11, every other or alternate chambers being connected with the same hub. Each bearing block 5 is provided with a downwardly extending radial port 12 which communicates at its inner end with the oil passage 13 in block 5. The oil passage 13 on each side of the machine is connected by a pipe 14 with a pressure control cylinder 15.

16 are teeth removably mounted on the perimeter of the scarifier D by means of their shanks extending inwardly through 85 snugly fitting holes in the walls of the chambers 10. The inner ends of said shanks are slotted to receive wedge keys 17 which securely, yet removably hold said teeth in place. Said teeth are provided with oil 90 passages 18 which communicate with the chambers 10 and discharge on the lower lateral face of the teeth.

It is evident that a chamber 10 will receive a charge of oil only when it is at the 95 lower most point and its feed tube 11 is in vertical registration with the port 12 of the block 5 with which said tube is connected. Thus a longitudinal row of teeth admit oil to the road surface only when they are 100 in engagement with said surface, the oil being at other times cut off from the row of teeth. One of the teeth is omitted in Fig. 3, to show more clearly the shape of chambers 10. Each of the cylinders 15 is provided 105 with an inlet port 19 near its discharge end, which inlet port is connected by a flexible connection 20 with an oil pump 21 suitably driven as by steam-engine 22. A supply pipe 23 provided with a valve 24 supplies 110 oil from a tank 25 carried by the surfacer B. Said oil or other hydrocarbon is pref-

erably supplied with a heating medium, such as steam, as through the pipe 26 and heating coil 27. The cylinders 15 are provided with resiliently mounted pistons 28 which relieve excess pressure where the hardness or nonabsorbing nature of the road surface cuts down the oil discharge through the passages 18 and also prevents knocking or hammering during the short intervals when oil is not being discharged through the teeth. The structure of the front scarifier C is similar to that of the rear scarifier D and the oil is supplied to its journal blocks through a pipe 29 leading at either side of the machine from the corresponding pipe 20. The rear scarifier D is suitably driven from the power plant 2 as by a train of gears in gear case 30 meshing with a beveled gear 31 on the end of said scarifier.

E is the tender box which sets on frame 1 and covers the rear scarifier. It may be used to hold fuel and water for the power plant.

32 is a coupling between the scarifier A and the surfacer B.

It is evident from the foregoing that by means of my machine the operations of scarifying, saturating and resurfacing can be done at one operation. With the attention of one man many miles of road may

be treated and completed in one day thus effecting a very substantial saving.

What I desire to claim is:—

1. In a road making machine, a rotary drum, teeth mounted radially on said drum adapted to scarify the road surface, said teeth being provided with passages, said means for injecting fluid hydrocarbon through said passages into road surface. 35 40

2. In a road making machine, a rotary drum, teeth mounted radially on said drum adapted to scarify the road surface, said teeth being provided with passages, and means for ejecting fluid hydrocarbon 45 through said passages when said teeth are in contact with the road surface.

3. In a road making machine, a rotary drum, teeth mounted radially on said drum adapted to scarify the road surface, said 50 teeth being provided with passages, means for ejecting fluid hydrocarbon through said passages when said teeth are in contact with the road surface, and means for cutting off the supply of hydrocarbon from the 55 teeth out of contact with the road surface.

Signed at Pittsburgh, Pa. this 13th day of May, 1914.

WILLIAM COOPER.

Witnesses:

A. W. FORSYTH,
E. A. LAWRENCE.

It is hereby certified that in Letters Patent No. 1,117,333, granted November 17, 1914, upon the application of William Cooper, of Denver, Colorado, for an improvement in "Road-Making Machinery," errors appear in the printed specification requiring correction as follows: Page 1, line 45, for the words "surface of" read *surfacer*; page 2, line 38, for the word "said" read *and*; and that the said Letters Patent should be read with these corrections therein that the same may conform to the record of the case in the Patent Office.

Signed and sealed this 8th day of December, A. D., 1914.

[SEAL.]

J. T. NEWTON,

Acting Commissioner of Patents.
